UNITED STATES PATENT OFFICE.

JAMES A. FAIRBANKS, OF AUGUSTA, MAINE.

PIPE-WRENCH.

SPECIFICATION forming part of Letters Patent No. 340,436, dated April 20, 1886.

Application filed November 11, 1885. Serial No. 182,443. (No model.)

To all whom it may concern:

Be it known that I, JAMES A. FAIRBANKS, of Augusta, in the county of Kennebec and State of Maine, have invented a new and useful Improvement in Pipe-Wrenches, which improvement is fully set forth in the following specification and accompanying drawings, in which—

Figure 1 is a longitudinal section through *y*, Fig. 2; and Fig. 2 is a cross section through *x x*, Fig. 1.

Like letters of reference indicate like parts.

In Fig. 1, *f* is the shank, having wooden handle *e* and ferrule *d* thereon. Integral with the shank *f* is the jaw *a*.

n is the shank, having second jaw, *b*, thereon. On the throat of the shank *n* are cut the screw-threads 1, 2, 3, &c. The bolt *c*, having external threads cut thereon, is placed between the shanks *f* and *n*. The threads on the bolt *c* engage those cut in the shank *n*. Upon one end of the bolt *c* is the milled head *r*, by which it is operated. The other end rests solid against the jaw *a* at 4. The whole is inclosed in the case *m m*, (the outline shown at *o o o o*.) The pin 8 passes through the case *m* and jaw *a*. Upon the case *m* is the rim *s*, through which passes the screw *k* into slot *i i*, cut in the bolt *c*, so as to allow a slight longitudinal motion of the bolt.

5 5 is a spiral spring resting in holes drilled in shank *f* and case *m*.

In Fig. 2 the case *m*, shanks *n* and *f*, and bolt *c* are shown in cross-section.

35 To give a quick return, the bolt *c* has the threads cut off, as indicated in Fig. 2, so that when the flat surface is turned to the flat surface of the shank *n* the shank will then slide freely in the case *m*.

40 My wrench operates as follows: To open or close the jaws, the bolt *c* is turned by the milled head *r*, the threads on the bolt engage those cut in the throat of the shank *n*, and the jaws *a b* are opened or closed, as desired. When 45 adjusted to the pipe or rod, the handle is pressed upward, (as drawn,) the pin 8 operates as a fulcrum, the jaw *a* at 4 presses against the bolt *c*, and as the bolt is allowed to slide in the case *m*, the slot *i i* being cut as before described, this operation closes the jaws on

the pipe or rod. There will also be a slight closing of the jaws due to the movement on the pin 8, before described.

The operation of a wrench having a quick return is readily understood by reference to Fig. 2. When the bolt *c* has the threads cut off on one side, as indicated in Fig. 2, the flat surface is turned parallel with the flat throat of the shank *n*. The shank can then be moved freely through the case *m*, and when adjusted to the pipe or rod the bolt is turned to the right, the thread thereon engages the thread in shank *n*, and the whole is locked and operated as before described.

I am aware that wrenches resembling this have been patented and are in use, and I wish to acknowledge the state of the art as represented thereby.

I distinguish my invention from all others, in that I employ a bolt with external screw thereon, which enables me to cut the screw-threads upon the throat of the shank *n*, and thus add to its strength and prevent injury to the threads in operating the wrench. It also enables me to make a more compact and stronger wrench; and, again, in having the jaw *a* at 4 operate against the head of the bolt *c*, this, it will be seen, slides the bolt, and consequently the shank *n* and jaw *b*, in the case *m*, thus closing the jaws on each other. The spiral spring is also an improvement.

I claim as my invention—

1. In a pipe-wrench, the combination, substantially as described, of the shank *f*, having jaw *a* thereon, the shank *n*, having jaw *b* thereon and screw-threads cut in the throat thereof, and the bolt *c*, with external screw thereon, all connected and inclosed by the pin 8 and case *m*.

2. In a pipe-wrench, the combination of the shank *f*, having jaw *a* thereon, said jaw operating against the bolt *c* at 4, as described, the shank *n*, with jaw *b* thereon and screw-threads cut in the throat thereof, and the bolt *c*, with screw cut thereon, all inclosed and connected by pin 8 and case *m*, as set forth.

3. In a pipe-wrench, the combination, as described, of the shank *f*, having jaw *a* thereon, the shank *n*, having jaw *b* thereon and screw-threads cut in the throat thereof, and the

bolt *c*, with external screw thereon, all inclosed, connected, and operated by case *m*, pin 8, and spiral spring 5.

4. In a pipe-wrench, the combination of the shank *f*, having jaw *a* thereon, the shank *n*, with jaw *b* thereon and screw-threads cut in the throat thereof, and the bolt *c*, with external screw thereon, the threads on said bolt being cut off on one side to give a quick return, all inclosed and connected by case *m* and pin 8, as described.

5. In a pipe-wrench, the combination of the

shank *f*, having jaw *a* thereon, the shank *n*, with jaw *b* thereon and screw-threads cut in the throat thereof, and the bolt *c*, with external screw thereon, said bolt having slot *i* cut therein to allow longitudinal motion thereof, all inclosed and connected by case *m*, pin 8, and screw *k*, as and for the purposes set forth. 15

JAMES A. FAIRBANKS.
